Fig. 4.

Fig. 5.

Fig. 6.

Fig. 7.

Fig. 1.

Fig. 2.

Fig. 3.

FIG. 1 is a top front perspective view of an electrical connector housing;

FIG. 2 is a bottom rear perspective view showing the housing of FIG. 1 rotated 180°;

FIG. 3 is a plan view looking down on the housing of FIG. 1;

FIG. 4 is a plan view looking up at the housing of FIG. 2;

FIG. 5 is a side elevational view looking in the direction of arrow 5 of FIG. 3;

FIG. 6 is a side elevational view looking in the direction of arrow 6 of FIG. 3 and rotated 90° clockwise; and

FIG. 7 is a side elevational view of the housing looking in the direction of arrow 7 of FIG. 3 and rotated clockwise 180°.

I claim:

The ornamental design for an electrical connector housing, substantially as shown.
